WRAPPING PAPER OR SIMILAR ARTICLE

Walter L. Wolf, Rydal, Pa., assignor to Wolf Brothers, Inc., Philadelphia, Pa., a corporation of Pennsylvania

Application March 12, 1953, Serial No. 23,998

Term of patent 14 years

(Cl. D59—2)

To all whom it may concern:

Be it known that I, Walter L. Wolf, a citizen of the United States, residing in Rydal, county of Montgomery, Commonwealth of Pennsylvania, have invented a new, original, and ornamental Design for Wrapping Paper or Similar Article, of which the following is a specification, reference being had to the accompanying drawing, which forms a part thereof, in which the figure is a plan view of a portion of wrapping paper or similar article, showing my new design. A design unit is shown within the broken lines and is repeated as indicated.

I claim:

The ornamental design for wrapping paper or similar article, as shown and described.

WALTER L. WOLF.
